[57] CLAIM

The ornamental design for a tray, substantially as shown and described.

DESCRIPTION

FIG. 1 is a perspective view of a tray showing our new design;

FIG. 2 is a front elevational view of the tray;

FIG. 3 is a side elevational view of the tray;

FIG. 4 is a bottom plan view of the tray; and

FIG. 5 is a cross-sectional view taken along line 5—5 as applied to FIG. 2.
